(57) **CLAIM**

The ornamental design for a wheel, as shown and described.

DESCRIPTION

FIG. 1 is an enlarged, partial view of the wheel of my design, as indicated by the break lines;

FIG. 2 is a front elevation view of the wheel of my design;

FIG. 3 is a perspective view of the wheel of my design;

FIG. 4 is a side elevation view of the wheel of my design; and,

FIG. 5 is a side elevation view of the wheel of my design, taken from the side opposite that shown in FIG. 4.

In the drawings, the dashed broken lines depict portions of the wheel that form no part of the claim. The thinner dotted lines in FIG. 1, which form no part of the claim, represent the boundary of the enlarged portion of FIG. 4 that is shown in FIG. 1.
